UNITED STATES PATENT OFFICE.

MAXWELL VIDAVER, OF NEW YORK, N. Y., ASSIGNOR, BY MESNE ASSIGNMENTS, TO VIDAVER MAILING MACHINE CO., INC., OF NEW YORK, N. Y., A CORPORATION OF NEW YORK.

AUTOMATIC STAMPING AND SEALING MACHINE.

Application filed March 27, 1925. Serial No. 18,686.

To all whom it may concern:

Be it known that I, MAXWELL VIDAVER, a citizen of the United States, residing at New York, in the county of New York and State 5 of New York, have invented certain new and useful Improvements in Automatic Stamping and Sealing Machines, of which the following is a full, clear, and exact description, such as will enable others skilled in the art 10 to which it appertains to make and use the same.

This invention relates to improvements in sealing and stamping machines and more particularly in some of its details to improvements in such machines for affixing one or more stamps upon envelopes or similar articles or packages or making an imprint thereon.

It is a general object of the invention to 20 improve and perfect machines of the class mentioned with a view to simplification in construction and operation and to assure positiveness in the performance of its various functions.

25 It is a more particular object to provide a machine of the class mentioned with a novel and effective mechanism for applying stamps or other designating devices or designations to envelopes or the like in accordance with the weight thereof or similarly to print a designation upon said envelope.

30 A further object is to provide an effective and satisfactory weight responsive control mechanism for machines of the class mentioned whereby stamp affixment or the placement of a printed designation is controlled by the weight of an envelope or article to apply stamps or make an imprint in accordance with the weight.

40 A further object is to provide an improved mechanism for machines of the class mentioned which is sensitively responsive to the weight of an article while the latter is being fed or advanced in the machine.

45 Still another object is to provide an improved stamp severing and feeding mechanism with control mechanism therefor whereby the severing operation is rendered more positive and certain.

50 It is another object of the invention to provide an improved stamp severing mechanism designed to exert a tearing effect upon the stamp strip, which may be perforated,

so as to increase the effectiveness and certainty of the severing operation. 55

Other objects will be in part pointed out in connection with the following detailed description and will be in part obvious in connection therewith.

The invention accordingly comprises the features of construction, combinations of elements, and arrangement of parts, which will be exemplified in the construction herein-after set forth and the scope of the application of which will be indicated in the claims. 60 65

For a more complete understanding of the nature and objects of the invention reference is had to the following detailed description of illustrative but preferred embodiments of the invention and to the accompanying 70 drawings, in which—

Figure 1 is a view of a sealing and stamping machine embodying the invention, the left part being in plan and the right part being in horizontal section just above the stamp severing, moistening and feeding mechanism so as to show said mechanism in plan, parts being broken away for clearness of disclosure, 75

Fig. 2 is a longitudinal vertical central 80 section of the machine,

Fig. 3 is a fragmentary detail view showing the adjustment of the flap moistening belt,

Fig. 4 is a fragmentary detail sectional 85 view of the stamp delivery and severing mechanism, the section being taken substantially on the line 4—4 of Fig. 1 looking in the direction of the arrow,

Fig. 5 is a fragmentary sectional view of 90 the stamp feeding mechanism, the section being taken substantially on the line 5—5 of Fig. 1 looking in the direction of the arrow,

Fig. 6 is a detail sectional view of the stamp moistening and carrying mechanism, 95 the section being taken approximately on the line 6—6 of Fig. 2 looking in the direction of the arrow,

Fig. 7 is a detail view of the automatic release for the stamp delivery mechanism, and 100

Fig. 8 is a vertical longitudinal section similar to Fig. 2 but showing a modification of the invention.

Referring to the drawing for a detailed description of the embodiments of the invention there shown, the frame is indicated 105

at 10 and the operating parts of the mechanism are suitably mounted in this frame. The feed table 11 of the machine is spaced above the base of the frame, being preferably arranged in horizontal position between the side walls of the frame, and a driving motor M and certain of the driving connections for the various operative elements are mounted in the space below this feed table.

It will be observed that Figs. 1, 2 and 8 of the drawing are partially diagrammatic for the purpose of facilitating a clear disclosure of the invention.

The driving motor M may be connected in any convenient manner to the various operative elements of the machine, the connections shown including a counter shaft 12 connected to be driven by the motor by a chain or similar belt 13 engaging suitable pulleys or sprockets on the motor shaft and counter shaft. The countershaft is in turn connected by a belt 14 to a main driving shaft 15 through suitable sprockets or pulleys. The various operative elements of the machine are driven from the main drive shaft 15.

Power leads or conductors 16 and 17 lead to a suitable source of electric energy, the conductor 16 being connected to one terminal of the motor and the conductor 17 being connected to one pole of a motor control switch 18, the other pole of said switch being connected by a conductor 19 to the other motor terminal.

The envelope feed mechanism.

The envelope is fed or advanced in its course through the machine over the feed table 11 by means of grippers which are preferably in the form of feed rolls including upper rolls 20 at the leading or forward part of the machine mounted on shafts 21 and cooperating with lower rolls 22 mounted on shafts 23, the bites between the cooperating upper and lower rolls being arranged substantially in the plane of the feed table or slightly thereabove so as to receive and grip the envelopes as they are advanced over the table. There may be any desired number of these pairs of leading feed rolls dependent upon differing conditions of operation and character of work, three pairs being shown in the drawing.

Beyond the leading feed rolls 20, 22 and adjacent the stamp carrying and applying mechanism there are additional pairs of feed rolls, two pairs of such rolls being shown and each pair including an upper roll 24 mounted upon a shaft 25 and a lower roll 26 mounted upon a shaft 27. These rolls may be provided with some form of yielding surfacing, such as rubber, and in addition to the feeding they function to seal the envelope flap against the body of the

envelope and to affix one or more stamps to the face thereof. All the feed roll shafts are suitably supported for rotation in the machine frame and the upper shafts 21 and 25 are preferably mounted for up and down movement to accommodate the reception of envelopes of different thicknesses, elongated upright slots 28 being provided in the side walls of the supporting frame for accommodating this movement of the roll shafts.

As appears clearly in Fig. 1 the bites of the leading feed rolls 20, 22 are positioned at one side of the path of the feed of the envelopes, terminating short of the flap so as not to contact with the latter during the first stages of feeding the envelope through the machine. An envelope E is shown in dot and dash outline in Fig. 1 as being gripped and fed by the leading rolls. The flap of the envelope F is also shown in dot and dash outline. As appears from this disclosure the envelope when fed at the leading end of the machine is gripped by the feed rolls only at the margin thereof opposite the flap so that the latter lies out of the range of contact of said rolls during the process of moistening the flap and for a period of time subsequently thereto. The next succeeding or following rolls 24, 26 are preferably positioned so that the bite thereof lies in the path of the flap F so as to engage the latter during the final feeding and sealing operations.

Each pair of feed rolls is preferably positively driven by suitable driving connections, such for example as that shown, including a belt or sprocket chain 29 connected to a sprocket 30 on the main drive shaft 15 and to driven sprockets 31 connected respectively to two adjacent lower roll shafts 23, as shown in Figs. 1 and 2. The extreme forward pair of feed rolls (see Fig. 1) is driven by a belt 32 connected to the adjacent lower roll shaft 23 through suitable pulleys or sprockets, and the two following pairs of feed rolls are driven from the adjacent roll shaft 23 through belts 33 and 34 connected to sprockets on the shafts 23 and 27. In this manner all the rolls are driven at the same feeding speed from the main drive shaft.

Flap moistening and sealing.

The sealing and moistening mechanism for the envelope flaps (see Figs. 1, 2 and 3) includes a flap separator or deflector plate 35 having a curved leading edge or nose lying close to the feed table 11 and adapted to engage under the flap of the advancing envelope to raise or separate it from the body of the envelope. In this connection it will be noted that each envelope is fed into the machine with its flap facing upwardly and lying in position against or close to the body of the envelope. The envelope is introduced

to the machine with the flap attached edge lying close to the guide plate 36. As the envelope advances the flap is separated from the body thereof by the upwardly inclined 5 surface of the deflector plate 35. The gummed underside of the flap is moistened by means of a moisture carrying pad or belt 37, preferably of absorbent material and mounted for movement transversely of the 10 direction of envelope advancement, being guided and supported in a transverse channel plate 38 lying just above the feed table 11. The rear or following edge of the deflector plate 35 preferably overlies and is 15 attached to the channel guide plate 38, the upper reach of the moistening belt lying above the plate 35, while the lower reach lies within the channel of the guide plate 38. A guiding and pressing plate 39 shown as 20 attached to a transverse supporting bar 40, and having spaced forwardly facing rounded noses, is spaced just above the moistening belt, thus assisting in pressing the gummed surface of the flap into contact with the 25 moistening belt as the envelope is fed forwardly. It will thus be seen that the moistening belt moves relatively to movement of the envelope so there is a sliding or wiping contact between the belt and the gummed 30 surface, resulting in a more effective moistening action. A downwardly inclined deflector plate 41 may be arranged to engage the envelope flap as it passes beyond the moistening belt in order to prevent the flap 35 from contacting with the roll shafts 21, but it will be observed that there is considerable space between the lower edge of this deflector plate and the table 11 so the flap is not pressed into contact with the envelope 40 at this point.

The moistening belt 37 passes over and is driven by a pulley 42 mounted for rotation in a moisture receptacle 43 so as to carry the belt through the moisture. The pulley 42 is driven through a shaft and beveled gear connection 44 driven in any suitable manner by the machine. The moistening belt passes from the pulley 42 to the channel guide plate 38 over guiding bars or rollers 45, and at 45 its forward end over a roll or smoothed bar 46. One or both of the guide bars or rolls 45 may be adjustable, as by means of adjusting screws 47, so as to vary the tension thereof, and also to press or otherwise remove more or less of the moisture from the belt so as to vary the moistening effect on the gummed flap. Moisture falling from the belt will be caught in the channel of plate 38 and conducted back into the moisture receptacle 43.

It may sometimes be advantageous to employ an envelope guide plate at the opposite side of the feed table 11 from guide plate 36, and for this purpose swinging guide plates 48 spaced along the feed table may be em-

ployed, being pivoted to the adjacent side plate as at 49 so they may be swung upwardly (see Figs. 1 and 2). The forward ends of these guide plates 48 are preferably inclined at the lower and inner edge so an 70 advancing envelope of extra width may contact therewith to lift the guide plates upwardly out of the path of the envelope. Auxiliary guide plates 48' may be employed adjacent each guide plate 48 but more widely 75 spaced from the guide plate 36 so as to act as guides for extra width envelopes.

For some classes of work it may be desirable to apply a liquid adhesive to the flaps instead of moistening a gummed flap as 80 above described, and in such cases the belt 38 may be utilized to apply such liquid adhesive which may be contained in the receptacle 43. Reference to moistening in both specification and claims, and in connection 85 with both the sealing and stamp affixing mechanisms, will therefore be understood as comprehending both of these methods of rendering the flaps or stamps adhesive.

It will be seen that the arrangement of 90 the bites of the feed rolls as above described, provides a considerable space beyond the moistening belt 38 in which the flaps are not pressed against the body of the envelopes, thus providing a time interval after moistening before the sealing operation takes place. During this time interval the adhesive becomes softened, or the mucilage becomes partially set, and in either case the result is a 95 more certain and effective sealing when the 100 flap reaches the sealing rolls.

As the envelope is advanced by the leading feed rolls 20, 22, the flap encounters a deflector plate 50 positioned slightly in advance of the first pair of sealing feed rolls 105 24, 26 to deflect the flap downwardly into the bite of the rolls. The deflector plate 41, it will be observed, does not deflect the flap against the body of the envelope, the function of this deflector being to prevent flaps 110 from standing outwardly from the envelope so as to be obstructed by the roll shafts 21; ordinarily, the deflector plate 41 does not contact with the flaps. The sealing of the flap against the envelope is accomplished 115 when the flap enters the bites of the sealing rolls 24, 26.

Stamping mechanism.

The stamps are fed from a source of supply, preferably a perforated strip of stamps, detached from the strip, moistened and affixed or applied to the envelope without interruption to the progress of the latter through the machine. A mechanism for the 120 accomplishment of this feature is best shown in Figs. 2, 4, 5 and 6, and includes what may be termed the stamp moistening and feed mechanism (Figs. 5 and 6), and the stamp delivery mechanism (Figs. 2 and 4), 125 130

for delivery of the stamps to the feed mechanism as required for affixing to the envelopes.

The stamp feed and moistening mechanism includes cooperating upper and lower gripper feed rolls 51 and 52 respectively, a grooved stamp carrying wheel 53, and a carrier belt 54 passing intermediate the groove in the lower roll 52 in the groove of the carrying wheel 53 and over an upper pulley 55 mounted for rotation just below the feed table 11 adjacent the first pair of sealing rolls 24, 26. A belt-tensioning device 56 may be employed for properly tensioning the carrier belt 54. The stamp carrier belt passes over a medial channel in the lower feed roll 52 (see Fig. 5) and is driven by said lower feed roll which is carried by a shaft 57 suitably mounted in a supporting frame and driven by a chain belt 58 from a shaft 59, driven in turn from the main drive shaft 15 through intermeshing toothed gears 60, 61 (Fig. 1).

A stamp moistening roll 62 (Figs. 1 and 6) is also mounted upon the shaft 59 having a deep groove intermediate its ends, in which the carrier belt 54 is received. The stamp carrying wheel 53 and the moistening roll 62 are arranged with their peripheries lying approximately tangent to the same plane, the periphery of wheel 53 being opposed to the groove in the roll 62 (see Fig. 6). The moistening roll 62 dips into the compartment of a moisture receptacle 63 which for convenience in filling may extend beyond the side frame of the machine, as shown in Fig. 1. The moistening roll may be faced with moisture carrying resilient material.

Spring pressure plates (Fig. 6) are mounted to lie adjacent the moistening surface of the roll 62, being adapted for pressing the gummed surfaces of the stamps into engagement with the moistening surface of the roll. At the delivery end of the stamp feed mechanism adjacent the pulley 55 is a small roll 65 contacting with the carrier belt 54 for receiving the advancing edge of a stamp and directing it into the bite of the sealing rolls 24, 26 so said stamp is affixed to the face of the envelope which is being fed past this point. The upper stamp feed roll 51 is carried by a roll shaft 66 (Fig. 5) suitably mounted in a supporting frame and is preferably geared to the lower roll 52 through tooth gears 67. The roll 51 is resiliently pressed into gripping contact with the lower roll by means of adjusting springs 68, 69 at each end of the roll. One spring, as for example, 69, may be stiffer than the companion spring so as to hold the adjacent ends of the rolls into tighter contact than at the other ends so the corresponding edge of the stamp strip is gripped tighter at this point. A similar object may be accomplished with springs of equal strength but

adjusting the spring 69 to exert a greater pressure upon the corresponding end of the shaft than that exerted by spring 68. This arrangement permits a slight slipping or lagging of the stamp strip at the loose end 70 of the rolls resulting in a tearing action in severing the stamp strip, as more fully explained hereinafter.

The stamp delivery mechanism for delivering the stamps from a supply source to the stamp feed mechanism proper as best shown in Figs. 1, 2 and 4, includes gripping mechanism preferably cooperating gripping rolls 70, 71, one or both of which may be provided with serrated surfaces and the lower roll 70 being preferably grooved for the reception of a stamp supporting and guide plate 72 for directing the stamp strip into the bite of the rolls. These rolls are mounted on roll shafts 73, 74 carried by a suitable frame, and are preferably geared together through intermeshing gears 75. The upper roll 70 may be provided with resilient adjusting devices 76 similar to those above described for the roll 51, but adjusting devices 76 preferably apply equal pressure at both ends of the roll 70 so the stamp strip is gripped equally tightly at both edges.

Delivery rolls 70, 71 (see Figs. 1 and 4) are driven from the main drive shaft 15 through the gears 60, 61, idler gear 77 and a slip clutch connection to the roll shaft 74. This slip clutch includes a gear 78 mounted on the shaft 74 and meshing with the idler 77. The gear 78 is connected to the shaft 74 through friction collars 79, 80, the former being pinned to the shaft and the latter being in the form of a sleeve pressed into engagement with the side of the gear 78 by means of a spring 81 interposed between the sleeve 80 and a collar 82 pinned to the shaft.

An externally positioned hand knob 83 may be provided for manually feeding the stamps or adjusting the stamp strip into correct operative position with reference to the feed rolls 51, 52. The stamps are carried in a storage receptacle preferably a reel 84, and are preferably in the form of a perforated strip S arranged for unwinding from the reel.

The delivery rolls 70, 71 are provided with a retarding or checking mechanism, including, as best shown in Figs. 1, 2 and 7, a toothed wheel 85 having a periphery with one or more teeth indented therein, and a cooperating pivotal pawl 86 normally biased into holding position as by means of a spring 87, and which may as shown, be controlled by means of the electro-magnet 88.

For the purpose of notifying an attendant when the stamp strip is exhausted it is desirable to employ a signal device such as a bell 89 (see Fig. 2) with a pivoted spring-pressed clapper 90 having a shank or extension 91, the end of which overlies a slot 92

in the stamp guide plate 72. The clapper is normally held by the stamp strip out of contact with the bell, but when the strip becomes exhausted, the clapper is released 5 moving into contact with the bell and giving a signal, the shank 91 passing through the slot 92.

Control for stamping mechanism.

10 The control for the stamp delivering mechanism and hence of the affixing or applying of the stamp is preferably automatically accomplished by the envelope or article. Such control in the embodiment shown is effected either by virtue of the feeding movement thereof or by virtue of the weight, or by virtue of both the feeding movement and the weight of the envelope. For the accomplishment of this function, an embodiment 15 is shown including a pivoted operating member 93 (see Fig 2) having an operating arm 94 lying in the path of envelope feed and a switch blade or contact arm 95 which may be spring biased into normal operative position as shown. This operating member 20 may be mounted in any desirable position upon the machine, the showing of Fig 2 being partly diagrammatical. Lying in the path of contact arm 95 are resilient spaced contacts 96, 97 suitably mounted and insulated from each other. Contact 96 is provided on the upper side of its free end, in the path of the contact arm 95, with an insulation strip 98 for preventing electrical contact between the contacts 95, 96 when the former moves downwardly but permitting such electrical contact when the contact arm 95 moves upwardly.

For effecting the control by virtue of the 40 weight of the fed envelope, a weight controlled switch 99 is positioned so as to be subjected to the weight of the envelope as the latter is fed forwardly in the machine. This switch includes spaced insulated resilient contacts 100, 101 suitably mounted for operation by a plunger 102, at the upper end of which is a bearing plate 103 lying in the path of the envelope and having its upper face spaced just above the surface of the feed table 11. The forward surface of this bearing plate is preferably downwardly inclined so the advancing envelope contacts therewith and slides up over the surface thereof. The bearing plate 103 is positioned 45 (see Fig. 1) in the vicinity of the leading feed rolls 20, 22 so the envelope F is gripped at the margin thereof remote from the flap when it passes over the weight controlled switch. A spring 104 normally urges the operating plunger 102 to inoperative position, this spring being of a definite strength so the plunger is depressed when the envelope exceeds a predetermined weight.

60 The spacing of the consecutive pairs of leading rolls 20, 22, and the positioning of

the switch 99 relatively to the rolls is such that the envelope is gripped by the rolls at only one point at the time the envelope is positioned for exerting substantially its entire weight upon the bearing plate 103. The 70 roll bite being slightly above the surface of the feed table 11 and the upper surface of bearing plate 103 being also spaced above the feed table, it will be seen that practically the entire weight of the envelope rests upon 75 said bearing plate. A small proportion may be sustained by the gripping rolls, but a definite proportion of the envelope weight will be exerted upon the switch 99 which may be adjusted so as to operate to close contacts 100, 101 when the actual envelope weight reaches a predetermined value.

Referring to Fig. 2, a conductor 105 connects the contact arm 95 with the supply conductor 17 and conductors 106, 107 connect contact 96 with magnet 88. When contact arm 95 engages with the contact 96, the magnet 88 is thereby energized through the following circuits: conductors 17, 105, contact arm 95, contact 96, conductors 106, 107, magnet 88, and return conductor 108 to supply conductor 16. A cut-out switch 109 may be employed to render the control magnet 85 inoperative.

The spring contact 100 of weight control 90 switch 99 is connected to the magnet 88 by a conductor 110 and conductor 107, and spring contact 101 is connected to contact 97 by a conductor 111. When contacts 95, 97 are closed and contacts 100, 102 are simultaneously closed, it will therefore be seen that the magnet 88 will be energized through the following circuit: supply conductor 17, conductor 105, contact arm 95, contact 97, conductor 111, contacts 100, 101, conductors 110, 107, magnet 88, and return conductor 108 to supply conductor 16.

Automatic control of the machine.

It is found advantageous to start the envelope and stamp feeding mechanism when an envelope is introduced into the machine, and to stop the same when an envelope passes beyond the last pair of feed rolls. For accomplishing this feature, a simple and effective mechanism is employed including the switch 18 for controlling the motor M. This switch is operated through control mechanism including transverse shafts 112 mounted in the side plates of the machine frame and shown as disposed above the feed table 11, each shaft carrying one or more downwardly and rearwardly inclined arms 113. These shafts 112 are arranged in series, each being connected to an operating link 114 by suitable connecting arms 115 (see Fig. 2). The movable element of the switch 18 is connected for actuation by the link 114 through a connection 116. This controlling mechanism is biased so as to maintain the operat- 110 115 120 126 130

ing switch 18 in open position. Closure of the switch 18 energizes the motor and starts the machine in operation.

Operation.

The operation of the machine is partially embodied in the foregoing disclosure and will be readily understood particularly in connection with the following summary.

Assuming the machine to be at rest, an envelope with its address side down and its flap up and to the right, looking in the direction of advancement of the envelope E as indicated by the arrow at the upper left hand end of Fig. 2, is introduced manually to the leading feed rolls 20, 22, but just prior to engagement in the bite and while held by the operator the leading edge of the envelope encounters the first switch operating arm 113 raising it slightly from the position shown in Fig. 2 and closing the switch 18 to start the motor. It will be understood that the switch and switch operating mechanisms are very light with negligible inertia and friction whereby operation is readily effected by the envelope as described.

A cycle of operation of the machine to perform a complete sealing and stamping operation on a single envelope is thus initiated by manual means prior to envelope advancement by the feed mechanism, and automatically through the instrumentality of the envelope as the latter is introduced into the machine. When the motor starts power is transmitted to the main driving shaft 15 and the entire machine including both envelope and stamp feed mechanisms is thereby set in operation, the leading feed rolls 20, 22 then gripping the envelope to advance it into the machine. The rounded forward nose of the flap separator 35 engages beneath the flap of the envelope, carrying it up over the moistening belt 37 where it is moistened, the sealing then being accomplished as described above.

The successive switch operating arms 113 are close enough together so that one or more of them is always in contact with the advancing envelope, and the machine therefore continues the cycle of operation to advance the envelope continuously and progressively through the machine, the cycle being terminated when the envelope passes beyond the last arm 113, the switch 18 then being opened automatically and the motor stopped. Each envelope may be ejected from the machine before a following one is introduced, the machine operating with rapidity for this purpose, and in this case the motor circuit will be broken between introduction of successive envelopes. The successive envelope may however be introduced before the preceding one has left the machine, so as to render the operation of the machine continuous, only the stamp delivery mechanism being then inter-

mittent through control thereof by each envelope in cooperation with the control arm 94.

The stamp delivering and severing mechanism are controlled by the fed envelope both through the weight control switch 99 and 70 through contacts 95, 96 which are closed when the fed envelope encounters the operating arm 94. Contacts 95, 96 are first closed by the advancing envelope and then opened immediately due to the movement of contact arm 95, thus momentarily energizing the magnet 88 and releasing the checking pawl 86 from engagement with a tooth of the ratchet 85. The pawl, however, in case the weight control switch 99 is not closed, is drawn at once into holding position by spring 87 thus engaging the next ratchet tooth that comes along and checking the delivery rolls 70, 71. This movement of the delivery rolls effects advancement of a predetermined length of stamp strip, ordinarily the length of one stamp, the forward end of the strip being introduced into the grip of the feed rolls 51, 52, which it will be remembered are continuously rotating during operation of the machine. In this connection it should also be observed that the friction clutch (Fig. 4) tends always to drive the delivery rolls 70, 71, these rolls being checked by operation of the holding pawl 86. Both pairs of stamp feed rolls are normally driven to advance the stamps at about the same rate, but when the pawl 86 checks the delivery rolls 70, 71, as described, a differential action is initiated in the rolls resulting in the exertion of a pull upon the advance strips severing one or more stamps along the perforations of the strip.

Due to the unequal gripping pressure at opposite ends of the gripping rolls 51, 52 above described, the tightly gripped edge of the strip has a tendency to feed slightly ahead of the loosely gripped edge, the result being that the severing pull is initiated at the tightly gripped edge and the pull is exerted differentially along the width of the strip, severance taking place with the tearing action. The pull required to sever is thus greatly reduced and the severing operation made more effective and certain.

When however the weight of the envelope exceeds a predetermined value, the contacts 100, 102 will be closed and this closure will be effected at the time the moving contact arm 95 contacts with the second contact 97. This second contact is timed to take place at the moment or just before the feeding of the first stamp has been completed, the roll 70 and ratchet wheel 85 having then, in the embodiment shown, made just under one-half revolution. The result therefore of closing both switches 99 and 95, 97 simultaneously is to energize the magnet 88 again through the circuit traced above so the pawl 86 is lifted over the next succeeding ratchet 130

tooth of ratchet wheel 85 and an additional stamp is thus fed forwardly by the delivery rolls. It will be observed that the stamps thus fed will be unsevered from each other.

5 Should it be desired that these stamps be severed from each other, this function could be accomplished by rearrangement of the teeth of the ratchet wheel, by changing the ratio of the feed rolls, or by varying the timing of the closing contacts. The severing of the plural stamp unit from the strip will be effected in the same manner as before described when the delivery rolls are finally checked by action of the pawl 86.

15 It will be thus seen that at least one stamp is always delivered by the delivery rolls and severed from the strip under control of envelope feed, and that an additional number of stamps is delivered and severed under 20 joint action of envelope weight and envelope feed in case the weight reaches a predetermined value.

When the trailing end of the envelope passes the operating arm 94, the contact arm 25 95 returns to normal position under its bias. Closing of circuits through the magnet in this return movement is prevented because the weight switch 99 opens as soon as the envelope passes it, and furthermore because 30 electrical contact between contacts 95, 96 is prevented by the insulation 98.

It is to be noted that the envelope feed mechanism and the stamp carrying mechanism, including the stamp delivery rolls, are 35 continuously connected for operating by the main drive shaft, there being no intermediate connecting or disconnecting driving connections or clutches with the exception of the simple slip clutch mechanism for effecting retardation of the delivery rolls.

Upon or just prior to the severance of a stamp from the strip as described, the severed stamp is gripped along a medial zone or strip between the carrying wheel 53 and belt 54, the projecting edges of the stamp presenting strips or zones of the gummed surfaces which are pressed firmly into contact with the moistening surfaces of the rolls 62 by means of the spring pressure plates 64. It will be observed that the moistened adhesive parts of the stamps do not contact at all with the carrying wheel or belt, so 40 no gumming or corrosion of these or other parts of the machine takes place. The severed stamp is shown at S¹ in Fig. 6 as gripped by the carrying wheel and belt and with the gummed marginal surfaces thereof pressed into contact with the moistening rolls by means of the spring plates 64. The stamp is carried to the upper side of the carrying wheel where, guided by roll 65, it is introduced between the sealing feed rolls 24, 26 and pressed into contact with the advancing envelope. When the stamp reaches the 45 point for affixing, both it and the envelope

are advancing at the same rate there being no retardation of the feeding movement of either. The stamp is additionally pressed into position to assure firm contact by means of the last pair of feeding rolls 24, 26. 70

By means of the mechanism described it will be noted that the envelope feed and stamp carrying mechanism are synchronized so both stamp and envelope arrive at rolls 24, 26 at a time so the stamp is applied to 75 the desired zone of the envelope. Inasmuch as operation of the entire machine is initiated when an envelope is introduced, and terminated when the envelopes leaves the machine, it will be observed that the machine remains idle excepting at such times as it is performing an operation on an envelope, thereby avoiding useless wear and tear upon the machine and wasting of energy. 80

In Fig. 8 a modification of the invention 85 is disclosed for affixing or applying a printed character or insignia upon the envelope or package, instead of applying a stamp as described above. The stamp severing, stamp carrying and stamp applying mechanism are 90 omitted in this modification, but other parts of the mechanism and the control and operation thereof are similar to those described in the foregoing disclosure, and similar reference characters with an index "a" are employed to designate corresponding parts. 95

In the embodiment shown a printing cylinder or member 120 is rotatably mounted in the frame of the machine having printing plates 121 secured thereto with printing surfaces disposed to pass adjacent to the path of the advancing envelope and substantially in line with the bites of the feed rolls. A rotatable pressure roll 122 overlies the printing cylinder 120 to press the envelope 100 into contact with the printing plates. The printing cylinder 120 and cooperating pressure roll 122 may be substituted for one pair of feed and sealing rolls 24, 26, or may be additional thereto. An inking device may 105 be mounted for supplying ink to the printing plates, this being shown in the form of a roll 123 having an ink pad mounted on the surface thereof and lying in position to contact with the printing plates 121 so as 110 to press against the latter and be driven frictionally thereby. 115

The shaft 74 corresponds to the shaft 74 shown in Fig. 4, except that the stamp rolls and mechanism associated with the latter are omitted. Shaft 74^a is driven from the main power shaft 15^a by a belt 124 connected to the slip clutch wheel 78^a and the printing member 120 is driven by a belt 125 passing over a pulley secured to the shaft 74^a. The ratchet and pawl mechanism 85^a, 86^a, is similar to that described above and the control switches 93^a and 99^a are arranged as above described, except that they are positioned 120 farther along the feed table 11^a in order that 125 130

the timing of the printing mechanism may be properly controlled. It will therefore be seen that the printing member 120 will be controlled to apply one or more printing indicia to the passing envelope, such control, both by the feed of the envelope and by the weight thereof, being similar to that described in connection with the preceding modification. That is, the printing member 10 120 rotates these 180° to print a single impression if the weight controlled switch 99^a is not closed but if this switch is closed two consecutive impressions are printed due to the fact that printing member 120 then 15 makes a complete revolution.

The printed indicia may include data indicating amounts of postage paid, and a counter or registering device 126 may be connected for operation by the shaft 74^a so 20 as to preserve an accurate record of the designated postage. Such register may be protected so as to be accessible for adjustment or setting only by government authorities or those especially authorized.

25 Although the invention has been described above with special reference to a machine for operating on mail matter, it will be obvious that it is applicable to other classes of work where it is desired to accomplish a 30 sealing function, or the function of applying some manner of indicia, or to accomplish both of these functions. It will be understood therefore that the terms "envelope," "stamp" and similar expressions are employed in the foregoing description and in the claims in a generic sense. Also it will be clear that the invention comprehends sealing alone, or stamping or printing alone, but the two functions are advantageously 35 combined for execution in a single continuous operation as in the machine set forth.

40 Since certain changes may be made in the above construction and different embodiments of the invention could be made without departing from the scope thereof, it is intended that all matter contained in the above description or shown in the accompanying drawing shall be interpreted as illustrative and not in a limiting sense.

45 It is also to be understood that the following claims are intended to cover all of the generic and specific features of the invention herein described, and all statements 50 of the scope of the invention which, as a matter of language, might be said to fall therebetween.

Having described my invention what I 55 claim as new and desire to secure by Letters Patent is:

60 1. In a machine of the character described, in combination, means for feeding an envelope, means for applying a stamp to said envelope, and means responsive to the weight 65 of the envelope being fed for controlling

stamp application by said applying means and being operative to vary control of said applying means while said feeding means continues feeding of the envelope.

2. In a machine of the character described, in combination, means for feeding an envelope, means for applying a stamp on said envelope and means responsive to the weight of the envelope being fed and responsive to feeding movement of said envelope for controlling stamp application by said applying means, said controlling means being operative to vary control of said applying means while said feeding means continues feeding of the envelope.

3. In a machine of the character described, in combination, means for feeding an envelope, means controlled by each individual envelope fed for affixing a stamp to each envelope, and means controlled by each individual fed envelope for affixing an additional stamp when the envelope weight exceeds a predetermined value.

4. In a machine of the character described, in combination means for feeding an article, means for applying a designation to an article and means responsive to the weight of the fed article for controlling application by said designation applying means, said weight responsive means being operative to vary control of said applying means while said feeding means continues feeding of said article.

5. In a machine of the character described, in combination, means for feeding an article, means controlled by each individual article fed for applying a designating character to each article, and means responsive jointly to article feed and to article weight to control said applying means.

6. In a machine of the character described, in combination, means for feeding an article, means controlled by each individual article fed for applying a designating character to each article, and means controlled by weight of a fed article to control said applying means so as to alter the applying operation thereof when the weight of the article exceeds a predetermined value.

7. In a machine of the character described, in combination, means for feeding an article, means controlled by each individual article fed for applying a designating character to each article, and means responsive jointly to article feed and to article weight to control said applying means so as to alter the applying operation thereof when the weight of said article exceeds a predetermined value.

8. In a machine of the character described, in combination, means for feeding an article, means controlled by each individual article fed for affixing a stamp to each article, a weight responsive element over which said article passes while fed and be-

ing subjected to the weight thereof, and connections between said weight responsive element and said stamp affixing means for controlling the latter in accordance with the 5 weight of said article.

9. In a machine of the character described, in combination, means for feeding an article, means controlled by each individual article fed for affixing a stamp to each 10 article, a weight responsive element over which said article passes while fed and being subjected to the weight thereof, a switch controlled by said weight responsive element and an electro-magnetic control device for 15 said stamp affixing means controlled by said switch.

10. In a machine of the character described, in combination, means for feeding an envelope, means for affixing a stamp to 20 said envelope including a stamp carrier and a stamp delivery means for delivering stamps to said carrier, an electro-magnetic control device for said stamp delivery means and control means for said electro-magnetic 25 control device under joint control of envelope feed and envelope weight.

11. In a device of the character described, in combination, means for feeding an envelope, means for affixing a stamp to said 30 envelope including a stamp carrier and a stamp delivery means for delivering stamps to said carrier, a detent for said stamp delivery means, means for controlling said detent to check said stamp delivery means up- 35 on delivery thereby of a predetermined number of stamps, and means for controlling said detent in accordance with the weight of the fed envelope so as to deliver an additional number of stamps by said delivery 40 means.

12. In a device of the character described, in combination, means for feeding an envelope, means for affixing a stamp to said envelope including a stamp carrier and a stamp delivery means for delivering stamps to said carrier, means for controlling delivery of stamps by said delivery means in accordance with envelope feed, and means for controlling delivery of stamps by said 50 delivery means in accordance with the weight of the fed envelopes.

13. In a device of the character described, in combination, means for feeding an envelope, means for affixing a stamp to said envelope including a stamp carrier and a stamp delivery means for delivering stamps to said carrier, means for controlling delivery of stamps by said delivery means in accordance with envelope feed, and means for controlling delivery of stamps by said delivery means jointly in accordance with feeding of said envelopes and weight of said envelopes.

14. In a machine of the character described, in combination, means for feeding

an envelope, means for affixing a stamp to said envelope, means for severing a stamp from a supply strip by exerting a tearing pull upon said strip, and means responsive to the weight of the envelope for controlling 70 said affixing means.

15. In a machine of the character described, in combination, means for feeding an envelope, means controlled by each individual envelope fed for affixing a stamp to 75 each envelope, means controlled by each individual fed envelope for affixing an additional stamp when the envelope weight exceeds a predetermined value, and means for severing a stamp from a supply strip by exerting a tearing pull upon said strip.

16. In a machine of the character described, in combination, means for feeding an envelope, means for affixing a stamp to 80 said envelope including a stamp carrier and a stamp delivery means for delivering stamps to said carrier, an electro-magnetic control device for said stamp delivery means, control means for said electro-magnetic control device under joint control of 85 envelope feed and envelope weight, and means for severing a stamp from a supply strip by exerting a tearing pull upon said strip.

17. In a device of the character described, 90 in combination, means for feeding an envelope, means for affixing a stamp to said envelope including a stamp carrier and a stamp delivery means for delivering stamps to said carrier, means for controlling de- 95 livery of stamps by said delivery means in accordance with envelope feed, means for controlling delivery of stamps by said delivery means in accordance with the weight 100 of the fed envelopes, and means for severing a stamp from a supply strip by exerting a tearing pull upon said strip.

18. In a machine of the character described, in combination, a stamp affixing mechanism and separate means maintaining 110 a continuous grip upon a stamp supply strip for severing a stamp therefrom by exerting a tearing action initiated at one edge of said strip.

19. In a stamp feeding mechanism, in 115 combination, means for gripping a supply strip of stamps at spaced parts thereof and feeding said spaced parts at substantially the same rate, and means for initiating a differential action of said gripping means so as to exert a differential pull along the 120 width of the strip and to sever a stamp from the strip with a tearing action.

20. In a stamp feeding mechanism, in combination, spaced pairs of rolls for gripping 125 and feeding a supply strip of stamps, means whereby one pair of gripping rolls grips the stamp strip tighter at one edge of the strip, and means for driving said spaced rolls at different speeds.

21. In a stamp feeding mechanism, in combination, means for gripping a supply strip of stamps at spaced parts thereof and maintaining continuous grip thereon, means for operating said gripping means to advance the stamp strip, and means whereby said gripping means exerts a differential pull along the width of the strip so as to sever the strip with a tearing action.
22. In a stamp feeding mechanism, in combination, spaced pairs of rolls for gripping and feeding a supply strip of stamps, means for operating said rolls to advance the stamp strip, means whereby one pair of gripping rolls grips the stamp strip tighter at one edge, and means to initiate a differential action of said rolls to exert a pull upon the stamp strip.
23. In a stamp feeding mechanism, in combination, means for gripping a supply strip of stamps at spaced parts thereof, means whereby said gripping means exerts a differential pull along the width of the strip so as to sever the strip with a tearing action, stamp affixing means for affixing a stamp to an envelope, and means controlled by envelope weight for controlling the feeding operation of one of said gripping means.
24. In a stamp feeding mechanism, in combination, spaced pairs of rolls for gripping and feeding a supply strip of stamps, means for operating said rolls to advance the stamp strip, means whereby one pair of gripping rolls grips the stamp strip tighter at one edge, stamp affixing means for affixing a stamp to an envelope and means controlled by envelope weight for controlling the feeding operation of one of said pairs of rolls.
25. In a stamp feeding mechanism, in combination, spaced grippers for feeding a stamp strip and exerting a continuous gripping action thereon, means for operating said grippers so as to exert a pull upon the strip and means for initiating said pull at one edge of the strip so as to sever the strip with a tearing action.
26. In a stamp feeding mechanism, in combination, means for exerting a continuous gripping action upon a strip of stamps and means for exerting a pull initially at one edge of said strip as held by said gripping means so as to sever the strip by a tearing action.
27. In a stamp feeding mechanism, in combination, means for gripping a strip of stamps, a pair of gripping feed rolls for exerting a pull on said strip as held by said gripping means and means for effecting tighter gripping engagement of said rolls at one edge of the stamp strip whereby the strip is severed with a tearing action.
28. In a stamp feeding mechanism, in combination, a pair of delivery rolls for gripping and feeding a strip of stamps, automatic means for checking delivery of the stamp strip by said delivery rolls, and a pair of gripping feed rolls for exerting a pull upon said strip as held by said checked delivery rolls, and means whereby said gripping feed rolls grip the stamp strip tighter at one edge of the strip.
29. In a stamp feeding mechanism, in combination, means for gripping a strip of stamps, a pair of gripping feed rolls for exerting a pull on said strip as held by said gripping means, and means for effecting tighter gripping engagement of said rolls at one edge of the stamp strip whereby the strip is severed with a tearing action, said last mentioned means including adjustable springs for holding said feed rolls in cooperative gripping engagement.
30. In a stamp feeding mechanism, in combination, a pair of delivery rolls for gripping and feeding a strip of stamps, automatic means for checking delivery of the stamp strip by said delivery rolls, a pair of gripping feed rolls for exerting a pull upon said strip as held by said checked delivery rolls, and means whereby said gripping feed rolls grip the stamp strip tighter at one edge so as to initiate the pull at one edge of the strip, said last mentioned means including a resilient adjustable member for holding said feed rolls in cooperating gripping engagement.
31. In a machine of the character described, in combination, means for feeding an article, means for affixing a designating character to said fed article, a checking device normally positioned for checking said affixing means, and means controlled by said article for releasing said checking device.
32. In a machine of the character described, in combination, means for feeding an article, means for affixing a designating character to said fed article, a checking device normally positioned for checking said affixing means, and means responsive to article feed and to article weight for controlling said checking device.
33. In a machine of the character described, in combination, means for feeding an article, means for affixing a designating character to said fed article, a checking device normally positioned for checking said affixing means, means responsive to article feed for controlling said checking device, and means responsive to article weight for controlling said checking device in sequence with said first mentioned controlling means.
34. In a machine of the character described, in combination, means for feeding an article, means for affixing a designating character to said fed article, a checking device normally positioned for checking said affixing means, an electro-magnetic device for operating said checking device and a

7 circuit closure operated by said fed article for energizing and immediately deenergizing said electro-magnetic device whereby said checking device is momentarily released but at once assumes checking position.

8 35. In a machine of the character described, in combination, means for feeding an article, means for affixing a designating character to said fed article, a checking device normally positioned for checking said affixing means, an electro-magnetic device for operating said checking device, and means controlled by weight of the fed article for energizing said electro-magnetic device for releasing said checking device.

9 36. In a machine of the character described, in combination, means for feeding an article, means for affixing a designating character to said fed article, a checking device normally positioned for checking said affixing means, an electro-magnetic device for operating said checking device, a plurality of energizing circuits for said electro-magnetic device, one of said circuits being controlled by article feed and the other being controlled jointly by article weight and article feed.

10 37. In a machine of the character described, in combination, means for feeding an article, means for affixing a designating character to said fed article, a checking device normally positioned for checking said affixing means, an electro-magnetic device for operating said checking device, means for energizing said electro-magnetic device including a contact device controlled by article weight and a contact device controlled by article feed, said last mentioned contact device having a plurality of contact

15 points one of which is connected in series with said weight controlled contact device.

16 38. In a machine of the character described, in combination, means for feeding an article, means for affixing a designating character to said fed article, a checking device normally positioned for checking said affixing means, an electro-magnetic device for operating said checking device, a plurality of energizing circuits for said electro-magnetic device, one of said circuits being controlled by article feed and the other being controlled jointly by article weight and article feed, said circuits being closed sequentially in timed relation to the operation of said affixing means.

17 39. In a machine of the character described, in combination, means for feeding an article, means for affixing a designating character to said fed article, a checking device normally positioned for checking said affixing means, an electro-magnetic device for operating said checking device, energizing circuits for said electro-magnetic device, a contact controlled by article weight and closed only when the fed article exceeds a

predetermined weight, and a second contact device controlled by said article and adapted to energize said electro-magnetic device twice in succession in case said weight controlled contact is closed.

18 40. In a machine of the character described, in combination, means for feeding an envelope including a gripper adapted to grip the envelope at one margin thereof, means for moistening the envelope flap while fed, means for affixing a designating character to the envelope, and a control member for said affixing means operated by envelope weight while the envelope is held by said gripper and after the envelope has passed beyond said moistening means.

19 41. In a machine of the character described, in combination, means for feeding an envelope including a gripper adapted to grip the envelope at one margin thereof, means for affixing a designating character to the envelope, and a control member for said affixing means operated by envelope weight while the envelope is held by said gripper.

20 42. In a machine of the character described, in combination, means for feeding an envelope including a gripper adapted to grip the envelope at one margin thereof, means for moistening the envelope flap while fed, means for affixing a designating character to the envelope, a control member for said affixing means operated by envelope weight while the envelope is held by said gripper and after the envelope has passed beyond said moistening means, and means positioned beyond said control member for sealing the envelope flap against the envelope.

25 43. In a machine of the character described, in combination, means for feeding an envelope having its flap initially lying adjacent the envelope body, including a plurality of feeding grippers arranged in series, means for automatically deflecting said flap from the envelope body as the envelope is fed forwardly, adhesional means for rendering the flap adhesive while fed and while deflected by said deflecting means, the feeding gripper next following said adhesional means being positioned to avoid pressing the flap against the envelope, and flap sealing means positioned beyond said next following feeding gripper.

26 44. In a machine of the character described, in combination, means for feeding an envelope having its flap initially lying adjacent the envelope body, including a plurality of pairs of gripping feed rolls arranged in series, means for automatically deflecting said flap from the envelope body as the envelope is fed forwardly, moistening means for moistening the envelope flap while fed and while deflected by said deflecting means, said feed rolls next follow-

- ing the moistening means being positioned to avoid pressing the flap against the envelope and flap sealing means positioned beyond said next following feed rolls.
- 5 45. In a machine of the character described, in combination, means for feeding envelope including a plurality of pairs of feed rolls arranged in series, moistening means for moistening the envelope flaps 10 while fed, the said rolls next following the moistening means being positioned to avoid contact with the flap, and flap sealing means positioned beyond said next following feed rolls, stamp affixing means, and control 15 mechanism for said affixing means operated by envelope weight while the envelope is gripped by said feed rolls and after the envelope has passed beyond said moistening means.
- 20 46. In a machine of the character described, in combination, means for feeding an envelope including feed rolls for gripping and feeding the envelope, means for affixing a stamp to the envelope, and a control member for said affixing means operated by envelope weight while the envelope is being fed, said feed rolls then gripping the envelope only adjacent the margin thereof.
- 25 47. In a machine of the character described, in combination, means for feeding an article, means for applying with a rolling contact a designation to said fed article while being fed, operation initiating means for said applying means, and means including an electromagnetically controlled detent under automatic control of an article as fed by said feeding means for initiating an applying cycle and for automatically terminating operation thereof upon completion 30 of said cycle.
- 35 48. In a machine of the character described, in combination, means for feeding an article, means for affixing a designating character to said fed article, means normally biased for holding said affixing means inoperative, electro-magnetic means for releasing said holding means, and means controlled by an article as fed by said feeding means for energizing said electro-magnetic 40 means to release said holding means and to subsequently deenergize said electro-magnetic means.
- 45 49. In a stamp feeding mechanism, in combination, means for gripping a supply strip of stamps at spaced parts thereof, means for operating said gripping means to advance the stamp strip, means whereby said gripping means exerts a differential pull along the width of the strip so as to sever 50 the strip with a tearing action, and automatic means for initiating said differential pull.
- 55 50. In a machine of the character described, in combination, means for feeding an article, means for applying a designat-

ing character to said fed article, means controlled by an article as fed by said feeding means for initiating an applying cycle of operations of said applying means, and means controlled by the same said fed article for applying a successive designating character thereto. 70

51. In a machine of the character described, in combination, means for feeding an article, normally continuously operative 75 means for applying with a rolling contact a stamp to said fed article while being fed, normally inoperative delivery rolls for delivering a stamp to said stamp applying means, operation initiating means for said delivery rolls, and means under automatic control of an article as fed by said feeding means for controlling said operation initiating means to initiate a cycle of operation of said delivery rolls and for automatically terminating operation thereof upon completion 80 of said cycle.

52. In a machine of the character described, in combination, means for feeding an article, means for carrying and applying a stamp to said fed article, means for delivering a stamp to said carrying and applying means, operation initiating means for initiating a cycle of operation of said stamp delivering means and for rendering said delivering means ineffective upon completion 90 of said cycle, and means controlled by the same said fed article for applying a successive designating character thereto. 95

53. In a machine of the character described, in combination, means for feeding an article, means controlled by each individual article fed for applying a designation to each article and means controlled automatically by said article for changing the significance of the designation applied. 100

54. In a machine of the character described, in combination, means for feeding an article and means under automatic control of the article for applying one only or a plurality of stamps to said article during 110 a single passage thereof in the machine.

55. In a machine of the character described, in combination, means for feeding an article, means under automatic control of the article for applying a stamp to said article, and means under automatic control of said article for applying an additional stamp thereto during a single passage thereof in the machine. 115

56. In a machine of the character described, in combination, means controlled by each individual article for applying a designation thereto, and means controlled automatically by said article and responsive to weight thereof for changing the significance of the designation applied thereto. 120

57. In a machine of the character described, in combination, stamp applying means for applying stamps to articles, and 130

means controlled automatically by said articles for applying one only or a plurality of stamps to each article at a single operation thereon.

58. In a machine of the character described, in combination, stamp applying means for applying stamps to articles and operating to apply at least one stamp to each article, and means responsive to article weight for controlling said applying means to increase stamp application to an article exceeding a predetermined weight.

59. In a machine of the character described, in combination, stamp applying means for applying stamps to articles, and means under automatic control of said articles for applying stamps thereto in units of one only or in units of a plurality of attached stamps.

60. In a machine of the character described, in combination, stamp applying means for applying stamps to articles, and means under automatic control of said articles for severing stamps from a strip and applying them to said articles in units of one only or in units of a plurality of attached stamps.

61. In a machine of the character described, in combination, spaced grippers for feeding a stamp strip, one of said grippers having a pair of rolls having continuously cooperating gripping surfaces for gripping a stamp strip toward one edge thereof while the opposite edge remains comparatively free, and another of said grippers being operable to exert a pull upon the strip so as to sever it with the tearing action initiated at one edge.

62. In a machine of the character described, in combination, spaced grippers for feeding a stamp strip, one of said grippers including a pair of rolls having continu-

ously cooperating gripping surfaces for gripping a stamp strip toward one edge thereof while the opposite edge remains comparatively free, and another of said grippers including a pair of rolls having continuous gripping surfaces for gripping the stamp strip, and means for controlling the action of said last mentioned rolls so as to exert a pull upon the strip and sever it with a tearing action initiated at one edge.

63. In a machine of the character described, in combination, spaced grippers for feeding a stamp strip, one of said grippers including a pair of rolls having continuously cooperating gripping surfaces for gripping a stamp strip toward one edge thereof while the opposite edge remains comparatively free, and another of said grippers including a pair of rolls having continuous gripping surfaces for gripping the stamp strip, means for driving both pair of feed rolls for feeding the stamp strip at substantially the same rate, and means for initiating a differential action of said rolls so as to exert a pull upon the strip and sever it with a tearing action initiated at one edge.

64. In a machine of the character described, in combination, mechanism for feeding an article, means for initiating operation of the machine, including said feeding mechanism, by introduction of an article into position to be fed by said feeding mechanism, means for applying a stamp to said fed article, said stamp applying means including a pair of stamp delivery rolls, and means controlled automatically by the article being fed to initiate a delivery cycle of operations of said delivery rolls thereby controlling stamp application by said applying means.

In testimony wherof I affix my signature.
MAXWELL VIDAVER.
